UNITED STATES PATENT OFFICE

LOUIS DUFAY, OF VERSAILLES, FRANCE, ASSIGNOR, BY MESNE ASSIGNMENTS, TO OLD JEWRY TRUST LTD., OF LONDON, ENGLAND, A CORPORATION OF GREAT BRITAIN

PROCESS FOR THE OBTAINMENT AND MULTIPLICATION OF COLOR PHOTOGRAPHIC PROOFS AND PRODUCTS RELATING THERETO

Application filed April 23, 1923, Serial No. 634,185, and in France May 19, 1922.

It is known that sensitive emulsions can be used for photographic printings and particularly for obtaining two superposed images, these emulsions being spread on both faces of a very thin transparent or translucent film.

It has been proposed to use a transparent film provided, on each of its faces, with a layer of positive emulsion, and to place negatives taken simultaneously through colored selecting screens, one on each of the sensitive layers of the film, and to print the said layers. In order to prevent the light which impresses one of the sensitive layers from acting upon the opposite layer through the film supporting the layers, it has also been proposed to color the said film.

The present invention relates to an improved process for preventing the light which impresses one of the sensitive layers from acting upon the opposite layer, and this without having to color the supporting film. For this purpose, the sensitive layers themselves are colored with an inactive coloring material which can be eliminated when washing the proof, this coloring material being preferably tartrazine.

The invention is clearly illustrated in the accompanying drawings, in which:—

20 Fig. 1 is a transverse section of a film showing the transparent support and the two layers of sensitive emulsion,

Fig. 2 is a section of the same film, negative plates *d*—*e* taken through different colored screens being applied on each of the emulsions to permit of their exposure and printing with light.

As intimated the film forming the subject matter of the invention is composed of two layers of positive emulsion *b*—*c* separated from each other by a thin transparent layer *a*.

These layers *b*—*c* present this essential particularity that it will be impregnated with an inactivic colouring material. The colouring materials for that purpose may be derivatives of anilin, they must have a high dyeing power for gelatin, have no action on the sensitiveness of the silver salt and they must be automatically eliminated by simple

washing in pure water, such for instance as tartrazine.

On such sensitive layers, it will be possible to obtain on the obverse or reverse, simultaneously or successively, different positive images, or corresponding to differently selected negatives, since each of the elements of the double sensitive layer will form a screen opposite the other, the light rays having impressed one of the sensitive layers not being able to impress the sub-jacent, owing to the presence of the inactivic colouring material.

Of course, the two elements of the double sensitive layer can be dyed in two different inactivic colours, one of the elements in yellow for instance, the other in orange or in green.

After development and fixing in the usual manner of the double image, the washing will eliminate from the layer the soluble inactivic colouring material.

The photographic images are obtained on the double sensitive layer by a single development.

Of course, the duration of the development will vary according as it is desired to obtain a proof visible by reflection or a proof adapted to be projected or examined by transparency. In the first case, the development will be stopped as soon as the black image will appear by reflection in all its details, on the contrary it will be carried out to the fullest extent in the second case.

At this moment, one will thus have on one and the same support a double black silver image each of the two layers of which can be subsequently coloured in the desired tint by a suitable toning in the known manner. By a judicious choice of the toning tints adopted for each of the two elements of the double layer, one will obtain by optical fusion, an infinite variety of colourations and a practically satisfactory reproduction of the photographed colours. The tint of the tonings will of course be varied according to the effect to be produced or to the nature of the photographed subject.

The coloured proof thus obtained will then be finished if it is intended for projec-

tion or examination by transparency; if it is intended to be examined by reflection, it will be placed, in the wet state on a reflecting surface such as a sheet of couched or sized paper of any tint for instance with which it will immediately become integral and will contract upon drying a perfect adherence. The proof obtained may be caused to adhere on any support, wood, ivory, metal, porcelain, etc.

10 What I claim as my invention and desire to secure by Letters Patent is:—

15 In a process for the reproduction of color photographs on a transparent film bearing only one sensitive layer on each of its faces, impregnating the said sensitive layers with tartrazine, applying simultaneously corresponding negative plates on each of the sensitive layers, exposing the film and said negative plates to light, subsequently washing the film so as to eliminate the tartrazine contained in the said layers and differently coloring said layers.

20 In testimony whereof I affix my signature.

25 LOUIS DUFAY.
